 poration of Michigan

Application February 18, 1938, Serial No. 191,162

16 Claims.

(Cl. 112—2)

This invention relates to an upholstery machine adapted particularly, although not exclusively, for making upholstery for vehicle seat and back cushions.

An object of the invention is to provide a machine capable of producing upholstery units of tufted or pleat-like formation consisting of a foundation sheeting and a cover fabric, together with an interposed layer of padding, in an inexpensive, efficient and improved manner and to eliminate the necessity of forming independent tubes and nested seams and/or seam ridges in the material and then feeding independent and individual strips of padding into those tubes.

Another object of the invention is to provide a machine of the foregoing character having means for gripping the edges of the foundation sheeting to hold it taut while it is being fed through the machine, and separate feeding means for the work positioned above and below the same and engageable with the opposite faces of the work for feeding it through the machine.

A further object is to provide a machine having power driven scoring devices for scoring or marking the padding at predetermined points to permit the placing of the fabric pieces in their proper positions with relation to and for engagement by the sewing mechanism of the machine.

Another object of the invention is to provide a machine having transversely disposed sewing instrumentalities including vertically reciprocable needles, to which the work is fed and presser feet in front of said needles, together with positively driven rotatable members associated with the presser feet to compress the work prior to its engagement with the feet and sewing needles.

Another object of the invention is to provide a machine having superimposed sets of positively driven endless work feeding belts located in the spaces between adjacent needles, and a weighted frame structure associated with the upper set of belts to apply pressure to the top surface of the work through the medium of said upper belts.

A further object of the invention is to provide a machine having a stripper for automatically releasing the foundation sheeting from the taut applying gripping means after the upholstery material issues from the sewing mechanism.

The above and other objects and advantages of the invention will appear from the following description and appended claims when considered in connection with the accompanying drawings, forming a part of this specification wherein like

reference characters designate corresponding parts in the several views.

In said drawings:

Fig. 1 is a diagrammatic top plan view, partly in section, of a machine embodying the present invention.

Fig. 2 is a longitudinal sectional view taken substantially along the line 2—2 of Fig. 1, looking in the direction of the arrows.

Fig. 3 is an enlarged fragmentary vertical transverse section taken substantially along the line 3—3 of Fig. 2, looking in the direction of the arrows.

Fig. 4 is a perspective view, partly broken away, of the machine taken from the front or entrance end thereof.

Fig. 5 is an enlarged fragmentary transverse sectional view taken substantially along the line 5—5 of Fig. 4, looking in the direction of the arrows.

Fig. 6 is an enlarged fragmentary perspective view of the sewing heads or instrumentalities and their associated parts taken from the front side thereof.

Fig. 7 is an enlarged fragmentary perspective view of the sewing heads and associated parts, taken from the rear of the machine.

Fig. 8 is an enlarged fragmentary perspective view taken from beneath the machine and looking toward the front side of the sewing mechanism and associated parts.

Fig. 9 is a perspective view of one of the work pieces turned by the machine, taken after the sewing operation has been completed.

Fig. 10 is an enlarged fragmentary section of the work piece, taken substantially along the line 10—10 of Fig. 9, looking in the direction of the arrows.

Fig. 11 is a fragmentary side elevation showing a detail of one of the sewing instrumentalities and associated parts, taken substantially along the line 11—11 of Fig. 6, looking in the direction of the arrows; and

Fig. 12 is a vertical section, partly in elevation, taken substantially along the line 12—12 of Fig. 11.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose

of description and not of limitation, and it is not intended to limit the invention claimed herein beyond the requirements of the prior art.

In accordance with the present invention, the embodiment of the machine herein shown and described comprises a positive means for feeding in superimposed relation the foundation sheeting and the layer of padding in continuous lengths, and for also positively feeding a series of cover pieces laid substantially edge to edge upon the padding, to a series or battery of transversely disposed sewing mechanisms or instrumentalities. The machine also comprises endless taut applying means for the foundation sheeting which diverge slightly from the entrance end of the machine toward the sewing mechanisms to maintain the foundation sheeting stretched evenly during its travel through the machine. The machine also comprises positively driven scoring devices for marking the padding to ensure the proper placement thereupon of the cover material pieces, and positively driven presser rolls or disks to compress the material at the lines of stitching prior to the engagement of the material with the presser feet and associated sewing needles. The top series of belts for feeding the material are associated with a weighted frame to apply pressure to the material between the rows or lines of stitching to ensure positive movement, as a unit, of the three layers of material making up the work pieces. At the exit end of the machine behind the sewing mechanism there is provided a stripper bar which engages the work and strips or releases the foundation sheeting from the taut applying means.

Referring now particularly to the drawings, the entire organization of the present embodiment of the invention is shown diagrammatically in Figs. 1 and 2. The machine, as shown, comprises a horizontal bed or table 13 mounted upon uprights 14 and suitable frame structure, not shown. Mounted upon the table and spaced thereabove is a platform 15 which extends transversely over the table and provides means for supporting a pile of cover material pieces 16. At the front or entrance end of the machine and adjacent the front end of the table 13 there is provided a somewhat smaller supporting table 17 mounted upon upright supports 18 for supporting a roll of cotton batting or padding material 19 mounted upon a removable shaft 20 which engages uprights 21 extending above the table to maintain the roll in place. A roll of foundation sheeting 22 is supported upon an auxiliary platform 23 positioned beneath the table 17.

The sewing mechanism and associated instrumentalities of the machine are located at or adjacent the rear or exit end thereof and, as shown, are mounted upon a cross frame member or bar 24 carried by two metal uprights or standards 25, one at each side of the machine.

Adjacent the front or entrance end of the machine and near the front edge of the table 13 there is supported, in any convenient manner, a positively driven roll or drum 26. A similar roll or drum 27 is provided adjacent the rear end of the machine behind and beneath the sewing mechanism. These rolls may be in the form of a series of drums of like diameter which are mounted upon a common shaft and fixed thereto to rotate together as a unit with the shaft. A driven shaft 28 is mounted or journaled in the upright frame members 25 adjacent to the roll 27 and carries a series of spaced pulleys or drums 29

which are fixed to the shaft to rotate together as a unit with said shaft. Another driven shaft 30 is mounted beneath the table 13 and adjacent the roll 26.

5 A series of spaced endless belts 31 is provided. These belts engage the rolls or drums 26 and 27 and are driven thereby. The upper course of each of the belts 31 travels over the top surface of the table 13 and preferably in a groove formed 10 in the table (see Fig. 3), the lower course of the belt travelling below the table 13 and over one of the driven drums 29 and the driven shaft 30. The drums 29 and the shaft 30 together provide tensioning means for the belts 31 as well as 15 auxiliary driving means for said belts. To prevent lateral shifting of the lower courses of the belts, a pair of guide bars or fingers 32 is provided for each of the belts. These guide fingers are mounted upon a transverse rod or shaft 33, 20 see Figs. 2 and 3.

20 Adjacent each of the side edges of the table
13 there is provided an endless belt 34 which
engages the rolls 26 and 27, one of the drums
29 and the driven shaft 30. The upper course of
25 each belt travels over the table 13 and prefer-
ably in a groove or depression formed therein.

Referring particularly to Figs. 3 and 5, there is shown in detail one of a pair of endless belts 35 which extends lengthwise of the machine and is provided with two spaced rows of staggered pins or screws 36 having points projecting beyond the outer face of the belt. The belts 35 cooperate with the belts 34 as will be seen later and are driven by pulleys 37 mounted upon a shaft

35 38 adjacent the front end of the machine and by similar pulleys 39 mounted upon a shaft 40 adjacent the rear end of the machine. The shaft 40 is preferably slightly longer than the shaft 28 so that the pulleys 39 mounted thereon will be

40 spaced apart a greater distance than the pulleys 37 which are mounted upon the shaft 38. Thus the belts 35 and also the belts 34 diverge slightly outwardly from the front or entrance end of the machine at A to the rear or exit end thereof 45 at B, see Fig. 1. The courses of each of the

belts 35 pass above and below a preferably channel shaped longitudinally extending frame member 41, see Figs. 3, 5 and 8. Tensioning means for the belts 35 preferably comprise idler rolls 50 or disks 42 which are mounted upon a transverse shaft 43 and engage the belts between the spaced

rows of impaling pins or screws 36 carried by the belts. Tensioning means for the rear end of the belts 35 preferably comprises a fixed rod or shaft 44. Thus sufficient tension and pressure are applied to the belts 35 to cause the lower courses thereof to force the pins or screws 36 into the

foundation material or sheeting as it issues from the roll 22 and to hold said sheeting transversely taut during its travel through the machine. The base portions or webs of the channel members 41 serve to maintain the lower courses of the belts 35 in flat condition. As seen particularly in Fig. 5, the lower belt 34 at each side of the machine provides means into which the prongs or points of the pins or screws 36 may penetrate after they have pierced the foundation material or sheeting 22 and thus protect the bed of the machine.

70. Mounted above the bed or table 13 of the machine and extending from a point in advance of the sewing mechanism to a point behind said mechanism is a series of endless belts 46. These belts are spaced apart transversely 75 of the machine and are driven at their front

ends by a roll or drum 47 and at their rear end by a knurled surface roll or drum 48 (see Fig. 7) which is mounted upon the shaft 40 carrying the pulleys 39, previously referred to.

Referring particularly to Figs. 6, 7 and 8, it will be seen that a weighted frame structure is interposed between the upper and lower courses of the endless belts 46. As shown, this structure may comprise longitudinally spaced wood blocks 50 interposed between top and bottom longitudinally extending wood boards 51, the blocks in rear of the needle mechanism being mounted upon a loose or unsupported cross shaft 52 (see Fig. 7). A heavy metal bar 53 extends transversely of the spaced pairs of boards 51 and rests upon the lower boards of the pairs. It will be understood that the wood blocks 50 and the boards 51 are secured together at opposite ends and at intermediate points to provide a unitary frame, the front spacer blocks 50 of which are pivotally mounted upon a fixed cross shaft 54 secured at its opposite ends to vertically adjustable brackets 55 mounted upon a portion of the machine frame, see Fig. 4. Thus the weighted frame is, in effect, a floating unit fixed at its front end and free at its rear end, which applies weight and pressure to the lower courses of the endless belts 46 to hold the material in compressed condition in lines interposed between the sewing instrumentalities. Thus the upper set of belts 46 cooperate with the lower set of belts 31 to grip the work and convey the work pieces to and through the sewing mechanism and prevent any relative movement of the three laminations forming each of the work pieces, thereby ensuring even stitching through the several layers of material in predetermined spaced lines.

Referring again to Fig. 2, it will be seen that a pair of horizontal transverse rolls 56 and 57 which are mounted upon transverse driven shafts, support and drive a wide endless band or belt 53. The upper course of this belt travels over the table 17. The belt is driven through the medium of gears 59 and 60 and chain 61 from the roll 26 (see Fig. 1) to cause the belt 58 to travel in a clockwise direction and unwind or unroll the cotton batting 19 from its supporting roll.

The cotton batting is scored longitudinally at spaced points as shown at 62, Figs. 1 and 4, by means of a series of scoring disks 63 carried by the shaft 38. The shaft 64 carries a series of presser disks 65 each of which is arranged in front of and cooperates with a presser foot 66, as shown in detail in Figs. 11 and 12. These disks 65 are in line with the lines of scoring 62 and serve to compress the material of the work pieces so as to guide it properly under the presser feet 66, as clearly seen in Fig. 11. The shaft 64 and disks 65 are driven or rotated by a sprocket and chain driving connection 64a, 64b, see Fig. 6. The longitudinally aligned relatively sharp edged presser disks 63 and 65 successively compress first the padding layer and then both the top fabric and padding layer along the lines of stitching to form well defined grooves or troughs thereby facilitating stitching and formation as well as accentuation of the intervening tuft or pleat-like portions of the final article. The sewing instrumentalities or units of the present machine each comprises the usual needle bar support 67, needle bar 68 and needle 69. The needle bar and needle are capable of vertically reciprocating movement and are allowed a forward and rearward, tilting or swinging movement about the

pivot 70, see particularly Fig. 11. It will be noted that the presser feet 66 are forked at their forward ends and that one of the presser disks 65 is positioned between the forked ends of each presser foot to rotate therein.

Each of the needle bars is adapted to support one or more needles, dependent upon the number and proximity of the rows of stitching to be applied to the work. The needles 69 are supplied 10 with thread from spools 71 supported in conventional manner upon a horizontal shelf 72, the thread being guided by means of spaced guides 73 and 74. The looper mechanism (not shown) is located below the needles at the underside of 15 the work and the loopers are supplied with thread from spools 75 supported in usual manner upon a shelf 76 located in a convenient position between the uprights of the machine frame structure. The mechanism for operating the needles and loopers may be of conventional construction.

It is desirable to provide means for automatically stripping or releasing the foundation sheeting 22 from engagement with the pins or screws 25 of the taut applying endless belts. For this purpose, see particularly Figs. 1, 2 and 7, there is provided at the rear end of the machine a stripper which, as shown, comprises a rod or shaft 80 having a freely rotatable sleeve 81 thereon. The shaft 80 is mounted at its opposite ends upon the upright frame members 25. The finished work pieces pass beneath the stripper and engage the sleeve thereof which applies a downward pressure to the continuous strip of material, thus pulling the edges of the foundation sheeting free from the impaling means 36.

The operation of the machine is substantially as follows: A roll of foundation sheeting 22 is placed in position upon the supporting cradle 23 and the sheeting is drawn out and upward and laid over the lower series of endless belts 31. The edges of the foundation sheeting are inserted between the spiked belt 35 and the cooperating smooth belt 34 so that the pins or screws 36 in the belt 35 will penetrate the sheeting. The sheeting is stretched transversely into taut condition when applied to the points of the screws. As stated above, the belts 35 diverge outwardly from the front end of the machine toward the needle mechanism and thus serve to maintain the sheeting in taut condition. A roll of cotton batting 19 is now placed upon the conveyor belt 58 and supporting table 17 and unwound and laid over the sheeting 22. The two layers of material are drawn forwardly and passed between the superimposed upper and lower series of endless belts 46 and 31. The drive mechanism for the machine is now set into operation whereupon the cooperating upper and lower pairs of endless belts 60 move the interposed layers of material forwardly through the machine, while the rotating scoring disks 63 function to score the cotton batting at predetermined points, for example, along the lines 62. A supply of cover pieces 16 has been placed 65 upon the platform 15 and an operator at each side of the platform places a cover piece over the cotton batting, with the long edges of the cover pieces being placed in close proximity one to another. Each cover piece is notched out at its long edges so that the workman can align the notches with the scored lines formed in the padding and thus ensure the proper positioning of the cover pieces to be engaged at the proper points by the battery of needles. The presser disks 65 70 are being rotated and serve to compress the cover

fabric 16 and the cotton batting 19 so that it will enter beneath the presser feet 66 in proper condition to be engaged by the sewing needles 69. As the machine continues to operate a series of stitched upholstery pieces, such as the specimen piece in Fig. 9, issue at the rear or exit end of the machine. These pieces are connected together by continuous lengths of the foundation sheeting and cotton batting, the three being stitched together by longitudinal rows of stitching. As the work pieces issue from the machine the stripper bar 80, 81 engages the continuous length of work pieces and releases or withdraws the foundation sheeting from engagement with the taut applying pins or screws 36. The upholstery material or pieces may now be stacked in piles in the continuous lengths in which they issue or the several pieces may be separated by severing the foundation sheeting and cotton batting at points located between the adjacent cover pieces 16.

It will be understood that a common source of power is employed to operate the several conveyor belts, scoring disks and presser disks, as well as to operate the sewing needles and looper mechanism.

We claim:

1. In an upholstery machine for producing pleated upholstery of the type comprising a foundation sheeting, an intermediate layer of padding, and a cover fabric stitched together by spaced rows of stitching; the combination of stitch forming mechanism, a plurality of endless feed belts located above and below the material for feeding it to said stitch forming mechanism, a plurality of scoring disks engageable with the padding to score the same longitudinally at predetermined points, presser feet located in advance of the stitch forming mechanism, and rotatable presser disks associated with said presser feet for compressing the material in advance of and adjacent to said feet and prior to its engagement with said feet.

2. In an upholstery machine for producing pleated upholstery of the type comprising a foundation sheeting, an intermediate layer of padding, and a cover fabric stitched together by spaced rows of stitching; the combination of stitch forming mechanism, a plurality of endless feed belts located above and below the material for feeding it to said stitch forming mechanism, a plurality of scoring disks engageable with the padding to score the same longitudinally at predetermined points, presser feet located in advance of the stitch forming mechanism, and rotatable presser disks associated with said presser feet for compressing the material in advance of and adjacent to said feet and prior to its engagement with said feet, said scoring disks and presser disks being longitudinally aligned.

3. In an upholstery machine for producing pleated upholstery of the type comprising a foundation sheeting, an intermediate layer of padding, and a cover fabric stitched together by spaced rows of stitching; the combination of stitch forming mechanism, a plurality of endless feed belts located above and below the material for feeding it to said stitch forming mechanism, a plurality of scoring disks engageable with the padding to score the same longitudinally at predetermined points, presser feet located in advance of the stitch forming mechanism, and rotatable presser disks associated with said presser feet for compressing the material in advance of and adjacent to said feet and prior to its engagement with said feet, said scoring disks and presser disks being

longitudinally aligned and said stitch forming mechanism comprising needles aligned with said disks.

4. In an upholstery machine for producing pleated upholstery of the type comprising a foundation sheeting, an intermediate layer of padding, and a cover fabric stitched together by spaced rows of stitching; the combination of stitch forming mechanism comprising transversely spaced needles, mechanism for feeding said sheeting with the padding layer superimposed thereupon into position to receive the cover fabric and thence feeding the work to said stitch forming mechanism, means for compressing said padding layer along well defined lines spaced in accordance with the spacing of said needles and in line therewith, and means for compressing both said cover fabric and padding along well defined lines corresponding to the lines of stitching, each of said means comprising spaced sets of relatively sharp edged disks.

5. In an upholstery machine for producing pleated upholstery of the type comprising a foundation sheeting, an intermediate layer of padding, and a cover fabric stitched together by spaced rows of stitching; the combination of stitch forming mechanism comprising transversely spaced needles, mechanism for feeding said sheeting with the padding layer superimposed thereupon into position to receive the cover fabric and thence feeding the work to said stitch forming mechanism, and a plurality of relatively sharp edged power driven disks aligned with said needles and in advance thereof for grooving the cover fabric and padding layers prior to the stitching thereof, said disks being supported by a common drive shaft.

6. In an upholstery machine for producing pleated upholstery of the type comprising a foundation sheeting, an intermediate layer of padding, and a cover fabric stitched together by spaced rows of stitching; the combination of stitch forming mechanism comprising transversely spaced needles, mechanism for feeding said sheeting with the padding layer superimposed thereupon into position to receive the cover fabric and thence feeding the work to said stitch forming mechanism, relatively sharp edged power driven disks aligned with said needles and in advance thereof for grooving the cover fabric and padding layers prior to the stitching thereof, and presser feet associated with said needles and bifurcated to straddle said disks, said disks being supported independently of said presser feet.

7. In an upholstery machine for producing pleated upholstery of the type comprising a foundation sheeting, an intermediate layer of padding, and a cover fabric stitched together by spaced rows of stitching; the combination of stitch forming mechanism, a plurality of endless feed belts located above and below the material for feeding it to said stitch forming mechanism, a plurality of scoring disks engageable with the padding to score the same longitudinally at predetermined points, presser feet located in advance of the stitch forming mechanism, rotatable presser disks associated with said presser feet for compressing the material in advance of and adjacent to said feet and prior to its engagement with said feet, and means at opposite sides of the machine engageable with the foundation sheeting for stretching the same laterally during its passage through the machine.

8. In an upholstery machine for producing

pleated upholstery of the type comprising a foundation sheeting, an intermediate layer of padding, and a cover fabric stitched together by spaced rows of stitching; the combination of a stitch forming mechanism, a plurality of endless feed belts located above and below the material for feeding it to said stitch forming mechanism, a plurality of scoring disks engageable with the padding to score the same longitudinally at predetermined points, presser feet located in advance of the stitch forming mechanism, rotatable presser disks associated with said presser feet for compressing the material in advance of and adjacent to said feet and prior to its engagement with said feet, and endless belts having impaling means located at opposite sides of the machine engageable with the foundation sheeting for stretching the same laterally during its passage through the machine.

9. In an upholstery machine for producing pleated upholstery of the type comprising a foundation sheeting, an intermediate layer of padding, and a cover fabric stitched together by spaced rows of stitching; the combination of a work supporting bed, stitch forming mechanism adjacent one end of the bed, a series of endless feed belts extending longitudinally of the machine, the upper and lower courses of said belts being disposed above and below said bed and extending the full length thereof, a second series of endless feed belts located wholly above the bed and extending throughout a portion of its length, said first and second series of belts engaging opposite faces of the work to feed the same to the stitch forming mechanism, and movable impaling means located at opposite sides of said bed and diverging toward said stitch forming mechanism engageable with the foundation sheeting for stretching the same laterally during the passage of the work through the machine.

10. In an upholstery machine for producing pleated upholstery of the type comprising a foundation sheeting, an intermediate layer of padding, and a cover fabric stitched together by spaced rows of stitching; the combination of a work supporting bed, stitch forming mechanism adjacent one end of the bed, a series of endless feed belts extending longitudinally of the machine, the upper and lower courses of said belts being disposed above and below said bed and extending the full length thereof, a second series of endless feed belts located wholly above the bed and extending throughout a portion of its length, said first and second series of belts engaging opposite faces of the work to feed the same to the stitch forming mechanism, and means diverging toward the stitch forming mechanism for transversely stretching said foundation sheeting independently of the padding layer and cover fabric during the feeding thereof toward the stitch forming mechanism.

11. In an upholstery machine for producing pleated upholstery of the type comprising a foundation sheeting, an intermediate layer of padding, and a cover fabric stitched together by spaced rows of stitching; the combination of a work supporting bed, stitch forming mechanism adjacent one end of the bed, a series of endless feed belts extending longitudinally of the machine, the upper and lower courses of said belts being disposed above and below said bed and extending the full length thereof, a second series of endless feed belts located wholly above the bed and extending throughout a portion of its length, said first and second series of belts engaging op-

posite faces of the work to feed the same to the stitch forming mechanism, movable impaling means located at opposite sides of said bed engageable with the foundation sheeting for stretching the same laterally during the passage of the work through the machine, and means at the exit end of the machine and extending transversely thereof for stripping the foundation sheet from said impaling means, said stripping means comprising a telescoped bar and rotatable sleeve.

12. In an upholstery machine for producing pleated upholstery of the type comprising a foundation sheeting, an intermediate layer of padding, and a cover fabric stitched together by spaced rows of stitching; the combination of a work supporting bed, stitch forming mechanism adjacent one end of the bed, a series of endless feed belts extending longitudinally of the machine, the upper and lower courses of said belts being disposed above and below said bed and extending the full length thereof, a second series of endless feed belts located wholly above the bed and extending throughout a portion of its length, means located between the courses of said second series of belts for applying pressure to the work passing beneath said belts, said first and second series of belts engaging opposite faces of the work to feed the same to the stitch forming mechanism, and movable impaling means located at opposite sides of said bed and diverging toward said stitch forming mechanism engageable with the foundation sheeting for stretching the same laterally during the passage of the work through the machine.

13. In an upholstery machine for producing pleated upholstery of the type comprising a foundation sheeting, an intermediate layer of padding, and a cover fabric stitched together by spaced rows of stitching; the combination of a work supporting bed, stitch forming mechanism adjacent one end of the bed, means for feeding to the stitch mechanism the cover fabric and padding in superimposed relation to the sheeting, and means for transversely stretching the sheeting independently of the padding and cover fabric, said last named means comprising endless belts extending throughout a major portion of the machine length diverging toward the stitch forming mechanism and having devices to impale the sheeting along opposite edges thereof.

14. In an upholstery machine for producing pleated upholstery material of the type comprising a foundation sheeting, an intermediate layer of padding, and a cover fabric stitched together by spaced rows of stitching; the combination of a work supporting bed, stitch forming mechanism adjacent one end of the bed, a series of transversely spaced endless feed belts extending longitudinally of the machine, the upper and lower courses of said belts being disposed above and below said bed and extending the full length thereof, a second series of transversely spaced endless feed belts located wholly above the bed and extending throughout a portion of its length, means located between the courses of said second series of belts for applying pressure to the work passing beneath said belts, said means comprising longitudinal spacer members and a transverse weighted member interconnecting said spacer members, said first and second series of belts engaging opposite faces of the work to feed the same to the stitch forming mechanism, and movable impaling means located at opposite sides of said bed and diverging toward the stitch forming mechanism engageable with the foundation

sheeting for stretching the same laterally during the passage of the work through the machine.

15. In an upholstery machine for producing pleated upholstery material of the type comprising a foundation sheeting, an intermediate layer of padding, and a cover fabric stitched together by spaced rows of stitching; the combination of a work supporting bed, stitch forming mechanism adjacent one end of the bed, a series of transversely spaced endless feed belts extending longitudinally of the machine, the upper and lower courses of said belts being disposed above and below said bed, a second series of endless feed belts located wholly above the bed and extending longitudinally thereof, and a weighted generally rectangular frame structure for compressing said material having members extending transversely of the machine and a plurality of substantially parallel members extending longitudinally of the machine and below the upper courses of the second series of belts, said entire frame structure

being located in the space between the upper and lower courses of said second series of belts.

16. In an upholstery machine for producing pleated upholstery of the type comprising a foundation sheeting, an intermediate layer of padding, and a cover fabric stitched together by spaced rows of stitching; the combination of a work supporting bed, stitch forming mechanism adjacent one end of the bed, means for feeding to the stitch mechanism the cover fabric and padding in superimposed relation to the sheeting, and means located adjacent opposite sides of the machine extending longitudinally thereof throughout a major portion of the machine length and diverging toward the stitch forming mechanism for transversely stretching the sheeting independently of the padding and cover fabric, said stretching means having sheeting impaling members.

ELMER M. KENNEDY.
CECIL ANDERSON BOYD.
